UNITED STATES PATENT OFFICE.

CARL W. WEISS, OF BROOKLYN, NEW YORK.

METHOD OF AND APPARATUS FOR CASTING.

SPECIFICATION forming part of Letters Patent No. 470,525, dated March 8, 1892.

Application filed October 19, 1891. Serial No. 409,135. (No model.)

To all whom it may concern:

Be it known that I, CARL W. WEISS, of Brooklyn, in the county of Kings and State of New York, have invented certain new and useful Improvements in Methods of and Apparatus for Casting; and I do hereby declare that the following is a full and exact description thereof, reference being had to the accompanying drawings, and to the letters and figures of reference marked thereon, making a part of this specification.

The object of my invention is to produce an improved method of and apparatus for casting various articles, and particularly to facilitate the production of small articles—such as gear and counting wheels for registers and the like—in a finished condition ready for use in the machines for which they are designed without trimming or filing or any further treatment.

My improved method consists in forcing the material in a fluid state into the mold through a suitable ingate and in subsequently forcing a solid body outward through the material in the mold and through or into said ingate, thereby expelling and cutting off all superfluous material.

My invention further consists in the apparatus hereinafter described and claimed for carrying said method into effect.

In the accompanying drawings, illustrating my invention, Figure 1 is a vertical central section of the improved apparatus, the plungers being shown in elevation. Fig. 2 is a top view of the same. Fig. 3 is a section on the line *x x* of Fig. 2, parts being broken off to save space. Fig. 4 is a similar view on the line *y y* of Fig. 2. Figs. 5 and 6 are detailed sectional views on the lines *v v* and *w w*, respectively, of Fig. 2. Fig. 7 is a detailed central section of the lower portion of the melting-pot. Figs. 8, 9, and 10 are detail views of different parts of the mold represented as in position in Figs. 1 and 2; and Fig. 11 is a perspective of the article produced by such mold in the condition in which it comes therefrom.

Like letters and numbers of reference indicate like parts in the several figures.

A melting-pot 10 (see Figs. 1, 2, and 7) or other receptacle for the molten material is supported by a suitable frame or casing 11 in

position to be kept at the necessary temperature by a burner 12 or other convenient source of heat. In the bottom of the pot is formed a chamber 13 of uniform diameter, from the bottom or end of which extends a tube or conduit 14, which is provided, preferably above the normal level of the molten material in the pot, with a nozzle 15. A plunger 16 enters said chamber and is adapted to move therein, being guided by a cross-bar 17 and operated by a convenient handle 19, which may be pivoted at 20 on the upper portion of the pot or casing. The lower end of the plunger is bored axially, as at 21, to receive a valve 22, and is perforated laterally, as at 23, near the upper end of the axial bore. The valve may be held in place with sufficient freedom of movement by a pin 24, fixed in the upper end of the valve-stem and projecting into the lateral perforation 23. In order to prevent the accumulation in the chamber 13 of the usual gritty or other hard particles of greater specific gravity than the molten material, I form the bottom of the melting-pot proper with a depression or groove 10^a, surrounding the upper end of the chamber 13 and preferably having a wall between the groove and the chamber brought to an acute angle in cross-section, as shown in Figs. 1 and 7. The aforesaid particles as they descend will settle in the groove 10^a and may be removed from time to time.

The mold may be of any form and made up of such elements as may be rendered necessary by the configuration of the article to be produced. The elements are combined and secured together to form a mold, which is separable, preferably into two parts, which may be designated as *a* and *b*, respectively. The part *a* is apertured centrally, as at *c*, (see Figs. 1 and 3,) and is suitably formed to fit or communicate with the nozzle 15. The part *a* is carried by a bar 25, which is pivoted or hinged upon a pin 26, Fig. 2, and is provided with a suitable handle 27. The part *b* of the mold is carried by a bar 28, which may be hinged upon the same pin 26, and is provided with a handle 29. A pin 30 may be fixed to one of said bars to enter a hole 31 in the other to insure accurate alignment of the parts of the mold. In order that the bars may be adjusted in position to bring the aperture

in the mold into accurate alignment with the nozzle 15, the pivot-pin 26 is carried by an arm 32, bolted to a bracket 33, which is secured to the frame 11. The arm and bracket 5 are each slotted, as at 34 and 35, for the reception of the bolt 36. The part *b* of the mold is also apertured, as at *d*, Fig. 4, in line with the aperture *c* of the part *a* for the reception of a plunger 37, which is of sufficient length 10 to enter the aperture *c* when pushed in to its full extent and is of such size as to fit snugly therein. The plunger 37 is carried by a bar 38, which is pivotally supported, as at 39, upon the bar 28. A stop-pin 40 may be fixed to the bar 28 to prevent excessive movement of the bar 38.

Pivoted upon the handle 27 of the bar 25 is a lever 41, formed, as clearly shown in Fig. 5, with a shoulder 42 to engage the handle 29 of 15 the bar 28 to hold the parts of the mold tightly together and with a cam-shaped end 43 to act upon said handle to force the parts of the mold apart. A second lever 44 (see Fig. 6) is also pivoted upon the handle 45 to engage 20 the bar 38 and hold the same from movement with the end of the plunger in close proximity to the inner end of the ingate *c*, leaving only a very narrow space for the ingress of the molten material.

25 The mold, which is shown in position in Figs. 1 and 2, and which is designed for the production of the combined gear and number wheel, as shown in Fig. 10, is itself illustrated in Figs. 8 and 9. It comprises a body 50, which is screw-threaded to engage the bar 25, is adapted to receive the nozzle 15, is apertured, as at *c*, for the passage of the molten material and to receive with a snug fit the plunger 37, and is provided with an enlargement of the 30 bore to co-operate with the plunger 37 for the formation of the hub of the wheel and with radial slots for the formation of wings to connect the hub with the outer portion or the shell. The part *a* comprises, further, an annular disk 35 51, which is fastened to the bar 25 and is adapted to form the gear-teeth shown in Fig. 10. The part *b* of the mold is made up of a series of annular disks 52, 53, and 54 (shown in Fig. 10) and adapted to form the remaining 40 portions of the wheel, as shown in Fig. 11. I have described this mold simply for the purpose of making the practice of my improved method and the operation of the mechanism more easily understood; but it is obvious 45 that a mold of any other desired configuration might be used and any desired article produced, the mold being of such formation as to contain and permit the movement of a suitable plunger outward through 50 the ingate.

In the light of the foregoing description my improved method of casting may be described, briefly, as consisting in reducing the material to a fluid condition, forcing the fluid material 60 into a mold, and finally forcing a solid body outward through the mouth or ingate of the mold. This method not only insures the

complete separation of the superfluous material from the body of the article, leaving no projecting portions to be filed away; but it 70 aids materially in forcing the material into every part of the mold.

In the operation of the apparatus which I have shown as adapted for carrying my improved method into effect, the melting-pot being filled with the molten material, the bar is 75 swung against the nozzle 15 to cause the latter to enter the ingate of the mold, the bar 28 is locked to the bar 25 by the latch-lever 41 to hold the parts of the mold together, and 80 the plunger 37 is held in the position indicated in Fig. 1 by the engagement of the latch-lever 44 with the bar 38. The plunger 15, previously raised to allow the molten material to enter the lower portion of the pot, is 85 now depressed to force the material through the conduit 14 into the mold. The material usually sets immediately in the mold, and this being the case the mold is swung away from the nozzle 15, leaving the ingate filled with a 90 solid core. The plunger 37 is now forced inward, severing the very thin annulus of metal between itself and the inner end of the ingate and expelling the metal from the ingate. When the material has cooled sufficiently to permit 95 of the removal of the article from the mold, the latch-lever 41 is reversed to cause its cam portion 43 to act upon the bar 28 or its handle 29 to separate the parts of the mold and release the finished article.

The details of the construction may be varied widely to suit the requirements of different cases, the essential feature being the plunger fitting and moving through or into the ingate of the mold in a direction to expel 100 the superfluous metal from the ingate.

I claim as my invention—

1. The herein-described method of casting, which consists in reducing the material to a fluid condition, forcing the same into a mold, and forcing a solid body through the ingate of the mold outward to sever and expel the superfluous material, substantially as shown and described.

2. The combination of a two-part mold, 115 hinged bars carrying the several parts of said mold, and a latch-lever pivotally connected to one of said bars and provided with a locking-shoulder to engage and hold the other bar and with a cam to force said bars apart, substantially as shown and described.

3. The combination, with a mold having a suitable ingate, of a plunger adapted to enter and fit within said ingate and means to move the plunger outwardly through the ingate, substantially as shown and described.

4. The combination, with a mold perforated in the line of its ingate, of a plunger moving through said perforation and adapted to enter it and fit snugly in the ingate, substantially as shown and described.

5. The combination, with a receptacle for molten material and a mold perforated in the line of its ingate, of means to force the molten

material from said receptacle into said mold and a plunger moving through the perforation in the mold and adapted to enter and fit snugly in the ingate, substantially as shown and described.

5. The combination, with a mold having a suitable ingate, of a plunger adapted to enter and fit said ingate, a lever to move said plunger outward through said ingate, and a latch-lever to engage said first-named lever and maintain the end of the plunger in proximity to the ingate, substantially as shown and described.

10. The combination of a two-part mold, hinged bars, one of which bars carries the ingate portion of the mold and is adapted to present

the same to receive a supply of molten material and the other of which bars carries the other portion of said mold, the latter being perforated in the line of said ingate, and a 20 plunger carried by said second bar and moving in said perforation and adapted to enter and fit snugly in said ingate, substantially as shown and described.

15. In testimony whereof I have signed my name to this specification in the presence of two subscribing witnesses.

CARL W. WEISS.
